UNITED STATES PATENT OFFICE.

CHARLES BRYAN BILLINGHURST, OF PIERRE, SOUTH DAKOTA.

DEVICE FOR NEUTRALIZING SHOCK.

1,302,759.

Specification of Letters Patent.

Patented May 6, 1919.

Application filed August 20, 1918. Serial No. 250,684.

To all whom it may concern:

Be it known that I, CHARLES B. BILLINGHURST, a citizen of the United States, and a resident of Pierre, in the county of Hughes 5 and State of South Dakota, have invented certain new and useful Improvements in Devices for Neutralizing Shock, of which the following is a specification.

My invention is an improvement in devices for neutralizing shock, and has for its 10 object to provide mechanism in connection with motor vehicles of every type for neutralizing metallic vibration, wherein a non-metallic element is interposed between the body of the vehicle and the frame for interrupting and neutralizing the metallic vibrations.

In the drawings:

Figure 1 is a side view of a motor vehicle 20 provided with the improved device;

Fig. 2 is an end view;

Fig. 3 is an enlarged detail of one of the non-metallic elements, with parts in section;

Fig. 4 is a front view of one of the 25 hangers, with parts in section;

Fig. 5 is a vertical section through one of the elements and its hanger; and

Fig. 6 is a view similar to Fig. 3 of a modified construction.

In the embodiment of the invention shown 30 in Figs. 1 to 5, an inner frame 1 and an outer frame 2 are provided, the frame 1 fitting within the frame 2, and the frame 2 is connected to the axles 3 and 4 by the usual springs 5. A series of hangers is connected with the inner frame, each hanger in the present instance being of turnbuckle construction, consisting of two aligned rods 6 connected by a double sleeve nut 7, the meeting ends of the rods being threaded, as 40 shown, to engage the nut.

The outer end of each rod 6 is engaged with a socket 8, and one of the sockets is on the under side of the inner frame and the other is on the housing 9 to be presently described in detail. Set screws 10 are threaded through the sockets into engagement with the rods for holding them in adjusted position, and it will be obvious that the length 50 of the hangers may be adjusted by turning the double nut in the proper direction.

A second casing 11 is secured to the outer frame 2 directly above each casing 9, and it will be noticed, referring to Figs. 3 and 4, 55 that the contour of these casings is approximately semi-circular, the flat side of the

hanger 11 being secured to the frame 2, while the flat side of the hanger 9 is downward. Each casing has thus a rounded or arc shaped surface, and these surfaces are 60 adjacent.

A disk 12 of rubber or like flexible resilient material is arranged within each casing, and these disks are connected by a belt 13 which passes over the disks in the same manner that a belt passes over a pair of pulleys. The disks are held from rolling movement in the casings by means of screws 14 which are passed through the front of the casing and through the disks into engagement with 70 the rear or inner wall of the casing.

Referring to Figs. 3 and 5, it will be noticed that the front or outer wall of each casing 9 and 11 is slotted transversely, so that a portion of each disk and a portion of 75 the belt at the disk is visible. The front portions of the casing are detachable as shown, to permit removal of the disk when desired, and the rounded surfaces of the casing are slotted to permit the passage of 80 the belt.

In the embodiment of the invention shown in Fig. 6, the casings 15 and 16, which correspond to the casings 9 and 11, are rectangular in outline, and instead of disks 12 there 85 are provided blocks 17 which have a flat or plane surface for engaging the end of the casing and a rounded surface for engaging the end of the belt 18. The blocks are held from movement in the casings by means of 90 screws 19 which correspond to the screws 14 of Fig. 5.

As many of the hangers may be provided as may be necessary, in the present instance six being provided, two at each side of the 95 frame and one at each end. Thus the inner frame which carries the body of the vehicle is suspended from the outer frame, by the belts which are of leather or like flexible non-metallic material, and the belts engage 100 the resilient blocks or disks, which provides not only an interruption of vibration, but provides resiliency as well.

I claim:

1. In a motor vehicle, a device for neutralizing shock, comprising a frame adapted for connection with the body, a second frame connected with the running gear, a resilient non-metallic connection between the frames, said connection comprising hangers on one 105 of the frames, each hanger supporting a casing and the other frame having a casing ad-

jacent thereto, each casing carrying a disk of resilient material, and a belt of flexible material engaging each pair of disks and connecting the same, said hangers being adjustable in length, each consisting of a section detachably connected with the frame and another section detachably connected with the casing, and a turnbuckle connecting the adjacent ends of the sections.

10 2. In a motor vehicle, a device for neutralizing shock, comprising a frame adapted for connection with the body, a second frame connected with the running gear, a resilient non-metallic connection between the frames, said connection comprising hangers on one of the frames, each hanger supporting a casing and the other frame having a casing adjacent thereto, each casing carrying a disk

of resilient material, and a belt of flexible material engaging each pair of disks and connecting the same, said hangers being adjustable in length. 20

3. In a motor vehicle, a device for neutralizing shock, comprising a frame adapted for connection with the body, a second frame connected with the running gear, a resilient non-metallic connection between the frames, said connection comprising hangers on one of the frames, each hanger supporting a casing and the other frame having a casing adjacent thereto, each casing carrying a disk of resilient material, and a belt of flexible material engaging each pair of disks and connecting the same. 25 30

CHARLES BRYAN BILLINGHURST.
